UNITED STATES PATENT OFFICE.

WILLIAM C. HEDGCOCK, OF CHICAGO, ILLINOIS, ASSIGNOR TO AMERICAN STEEL
FOUNDRIES, OF NEW YORK, N. Y., A CORPORATION OF NEW JERSEY.

SIDE FRAME.

1,169,816.

Specification of Letters Patent.

Patented Feb. 1, 1916.

Application filed May 10, 1915. Serial No. 26,930.

To all whom it may concern:

Be it known that I, WILLIAM C. HEDGCOCK, a citizen of the United States, and resident of Chicago, in the county of Cook and State of Illinois, have invented certain new and useful Improvements in Side Frames, of which the following is a specification.

My invention relates to car trucks and has particular reference to a novel side frame 10 for use in connection therewith.

A desirable object in car truck construction is to provide side frames which shall combine the elements of rigidity, strength, 15 minimum weight and economy in construction. Some of these objects may be attained in the use of cast steel frames, but such frames are quite heavy and their cost is greater than that of a properly designed 20 frame of rolled or pressed material. In the construction herein disclosed I have provided for maximum strength by so locating the different elements as to secure the greatest efficiency. Furthermore, the disposition 25 of metal provides for great rigidity, and by welding the parts together the frame has the attributes of a single casting.

The invention will be more readily understood by reference to the accompanying 30 drawings, wherein—

Figure 1 is a side elevation of a car truck constructed in accordance with my invention, Fig. 2 is a plan view of the construction shown in Fig. 1, Fig. 3 is a section on the line 3—3 of Fig. 1, and Fig. 4 is a section on the line 4—4 of Fig. 1.

Referring more particularly to the drawings, it will be seen that I provide a compression member consisting of two angles, 40 each thereof having its long leg 10, placed vertically and its short leg 11, horizontally, the short leg having a bulb or stiffening flange 12, which projects downwardly. The two angles are placed back to back, as best 45 shown in Fig. 2, being separated at their middle portions by the upper ends of the struts which act as columns. These columns are likewise composed of angles of commercial form, each angle 13, being bent into 50 U-shape, the flange 14, being terminated just beneath the compression member, the other flange extending between the two angles forming the compression member and being spot-welded therethrough. At the lower 55 end the two angles are bent outwardly to

accommodate the vertical leg 15, of the tension member, which, as best shown in Fig. 3, is of T-shape.

At the ends, the compression members are arched or bent downwardly, as at 16, the vertical legs 10, thereof being spaced apart sufficiently to accommodate the leg 15, of the tension member, this member being likewise bent downward and serving as a jaw 17, between which a journal-box may be accommodated. Opposed to the jaw 17, is a jaw 18, which may be formed from a forging and welded to the tension member. As a means for attaching the journal box, I provide the apertured lug 19, as best shown in Fig. 4, this being welded to the tension and compression members above the journal box.

In order to provide a simple brake hanger bracket, I provide a bar 20, bent into U-shape, one leg of the U being welded to a column 13, the other leg being apertured to accommodate a pin 21. The brace member may consist of the bar 22, bent to the proper shape and having its lower end also welded 80 to the column 13. An aperture in the upper end of the bar registers with the opening in the bar 20. The free upper end of the bar 22, may be welded to the bar 20.

It will be noted that this frame is built up 85 from commercial shapes which may be economically produced, and that after being bent and combined in the form shown by welding, a rigid and substantially integral structure is produced. The cost of assembling 90 such a frame is relatively small, and as the greatest strength is possible for a given weight in the rolled material shown, such a frame will be found to be efficient and much more economical in first cost than frames 95 constructed in a different manner.

While I have referred to the shapes as being formed by rolling, it will be understood that they might be pressed with equal facility; also that the parts might be riveted together in some instances instead of welding, all without departure from the spirit of my invention.

I claim:

1. In a side frame, the combination of a compression member composed of two bulb angles placed back to back, a tension member of rolled or pressed form, and a strut interlocking the said compression and tension members, the parts being rigidly united to 110

- form a substantially integral structure, substantially as described.
2. In a side frame, the combination of a compression member composed of two angular shapes, a tension member of a single angular shape, one flange of said tension member being accommodated between the elements of the compression member at the ends of the frame, and a strut separating said members, said strut being composed of two angles, each of which is bent into U-shape, said members being then welded together and welded to the compression and tension members of the frame, substantially as described.
3. In a side frame, the combination of a compression member composed of a pair of bulb angles placed back to back, a tension member of T-shape, the leg of the T being accommodated between the two elements of

the compression member at the ends of the frame, and a strut composed of two members, the upper ends of which are accommodated between the elements of the compression member, substantially as described.

25

4. In a built-up side frame, the combination of tension and compression members and a strut, and a brake hanger bracket composed of a plurality of bars, one end of each of which is welded to the said strut, the other ends of said bars being spaced apart and apertured to accommodate a hanger pin, substantially as described.

Signed at Chicago, Illinois, this 6th day of May, 1915.

WILLIAM C. HEDGCOCK.
